UNITED STATES PATENT OFFICE.

HARRY M. TINKLEPAUGH, OF PRICHARD, PENNSYLVANIA.

SHINGLE-GAGE.

SPECIFICATION forming part of Letters Patent No. 738,256, dated September 8, 1903.

Application filed May 8, 1902. Serial No. 106,457. (No model.)

To all whom it may concern:

Be it known that I, HARRY M. TINKLEPAUGH, a citizen of the United States, residing at Prichard, county of Luzerne, and State 5 of Pennsylvania, have invented certain new and useful Improvements in Shingle-Gages, of which the following is a specification.

My invention relates to shingle-gages.

The object of the present invention is the 10 provision of an improved gage for use in shingling operations which will be of simple, durable, and inexpensive construction and adapted to be folded in compact form when not in use and intended for use to gage the 15 shingles in a novel manner, whereby the number of shingles put on a house by a workman can be greatly increased.

Having the foregoing object in view, the invention consists of a shingle-gage of improved and novel form, as fully set forth hereinafter and recited in the appended claims.

In the accompanying drawings, Figure 1 is a view illustrating the manner of use of the invention; Fig. 2, a perspective view of the 25 invention; Fig. 3, a view of the gage when folded; and Fig. 4 a detail on line 44 of Fig. 2.

The gage is by preference composed of two parts 1 and 2, hinged together by the rule-joint 3 and each provided with the vertical 30 web or flange 4 and the horizontal flange 5. At the corners of the horizontal web 5 of the section 1 and at the outer corner of the horizontal flange 5 of section 2 the metal comprising the sections is provided with downwardly-struck points 6, which are intended 35 to be driven into the shingles last laid after the application of the gage thereto, and nail-holes 7 are also provided in the horizontal flanges 5, through which nails can be driven 40 to assist in holding the gage in position, if desired. On the flange 5 of section 1, adjacent the end thereof, and on the flange 5 of section 2, adjacent the outer end thereof, are boxes 8, having thumb clamping-screws 9, 45 said boxes being of inverted-U shape, with the flanges 10, which are secured to the flange 5, so that the boxes, together with the flange 5, provide a boxing having an elongated interior with an opening 11, which is rectangular. In these boxes are adapted to slide 50 and be secured by the thumb-screws the gage members 12, which are of the same size as

the openings 11 and provided at their outer ends with hooks or heads 13 and being also provided with graduations 14. In practice 55 the length of these gage members will be four inches and of the boxes 8 three inches, the boxes being also provided with graduations 15, so that on pulling out the gage members or pushing them in to any desired extent any 60 desired lap from three inches up to six inches of the shingles can be had, allowance of the additional inch of the gage members being for clamping by the thumb-screw.

The use of the invention will be apparent 65 from Fig. 1. When the lap of the shingles has been decided upon, all the gage members 12 are set for that lap. The gage is then applied by engaging the hooks or heads 13 over the lower end of the shingles previously laid 70 and the points 6 driven down to hold the gage. Nails can also be driven through the holes 7, if necessary. In practice each section of the gage will be two feet in length, so that the entire gage is four feet, and the next layer of 75 shingles will be placed with their lower ends resting against the flanges 4. After nailing of that row of shingles the gage is moved and placed on the row just nailed and another row of shingles nailed on. 80

I am aware that many changes of construction could be resorted to in carrying out my invention, and I do not, therefore, limit myself to the precise form herein shown and described, but consider that I am entitled to all 85 modifications falling within the spirit and scope of the invention.

Having thus described my invention, what I claim as new, and desire to secure by Letters Patent, is—

1. A shingle-gage consisting of two sections hinged together and adapted to work in the L of the vertical side of a house, boxes on each section and independent gaging means 90 slidably held in said boxes. 95

2. A shingle-gage comprising a body having vertical and horizontal flanges, fastening-points struck from said horizontal flanges, holes adjacent said points to admit of nails being inserted to assist in holding the gage in 100 position and means on said horizontal flange for adjustably gaging the body.

3. A shingle-gage having a body adapted to act as an abutment for the ends of the

- shingles, fastening - points struck from the body at right angles to the longitudinal plane thereof, and adjustable gaging devices on the body.
5. 4. A shingle-gage composed of a body having vertical and horizontal flanges, adjustable gaging devices on the horizontal flanges comprising boxes, and hook-arms slidably held in said boxes.
10. 5. A shingle-gage consisting of two sections hinged together, boxes on each section, independent hooked gage members slidable in said boxes, and means for securing said gage members in said boxes.
15. 6. A shingle-gage consisting of two sections hinged together, boxes on said sections, independent gage members having hooks and slid-
20 able in the boxes, and clamping-screws on the boxes adapted to clamp the gage members at different points to which said gage members may be adjusted.
7. A shingle-gage having a body composed of vertical and horizontal flanges, fastening points struck from said horizontal flanges, and means on the horizontal flanges for ad- 25 justably gaging the body.
8. A shingle-gage comprising a body having vertical and horizontal flanges, said vertical flange forming means for the abutment of the bottom of the next row of shingles to 30 be laid, boxes on the horizontal flanges, gage members adjustably held in said boxes, hooks on said gage members adapted to engage the last-laid row of shingles, and means for holding said gage members in their adjusted po- 35 sition.

In testimony whereof I hereunto affix my signature in presence of two witnesses.

HARRY M. TINKLEPAUGH.
